Patented Oct. 3, 1922.

Inventor
J. A. Sanner

By Watson E. Coleman
Attorney

UNITED STATES PATENT OFFICE.

JOHN A. SANNER, OF PAGE, WEST VIRGINIA.

TROLLEY POLE.

Application filed July 15, 1922. Serial No. 575,161.

To all whom it may concern:

Be it known that I, JOHN A. SANNER, a citizen of the United States, residing at Page, in the county of Fayette and State of West Virginia, have invented certain new and useful Improvements in Trolley Poles, of which the following is a specification, reference being had to the accompanying drawings.

10 This invention relates to certain improvements in trolley poles and has relation more particularly to a device of this general character especially designed and adapted for use in connection with mine locomotives and it is an object of the invention to provide a pole of this general character having novel and improved means whereby the same can be shortened as required and which is of particular advantage in a restricted passage.

20 Another object of the invention is to provide a novel and improved device of this general character comprising two sections connected for sliding movement one lengthwise of the other together with means for holding said sections in extended relation and wherein means are provided to limit the relative movement of said sections in opposite directions.

The invention consists in the details of construction and in the combination and arrangement of the several parts of my improved trolley pole whereby certain important advantages are attained and the device rendered simpler, less expensive and otherwise more convenient and advantageous for use, as will be hereinafter more fully set forth.

The novel features of my invention will hereinafter be definitely claimed.

30 In order that my invention may be better understood, I will now proceed to describe the same with reference to the accompanying drawings, wherein:

Figure 1 is a view in side elevation illustrating a trolley pole constructed in accordance with my invention with the sections thereof extended;

Figure 2 is an enlarged fragmentary view of my improved trolley pole as herein disclosed with the sections retracted; and

Figure 3 is a sectional view taken substantially on the line 3-3 of Figure 2.

As herein disclosed, T denotes a trolley pole particularly adapted for use with mine locomotives and which comprises two sec-

tions 1 and 2, the adjacent end portions of which being in overlying relation. The opposite faces *a* of the sections 1 and 2 are flattened so that said faces *a* when in overlying relation will have close contact one 60 with the other and at the same time hold the sections 1 and 2 against relative lateral or rotary movement.

Extending along the outer face of the inner end portion of each of the sections 1 and 2 is an elongated metallic strip 3 herein disclosed as integrally formed with a sleeve or cuff 4, said strip 3 and cuff 4 being secured to the section 1 or 2 by the rivets 5 or otherwise as may be preferred. The cuff or sleeve 4 is positioned immediately adjacent to the inner end of the section 1 or 2 and has freely and slidably disposed therethrough the other of said sections. The outer end portion of the member 3 terminates in an outstanding lip or lug 6 with which the cuff or sleeve 4 of the co-acting section of the pole is adapted to contact so that the inward relative movement of the sections 1 and 2 is limited. The cuffs or sleeves 4 contact 80 one with the other to limit the outward relative movement of the sections.

When the sections 1 and 2 are at their limit of outward movement and which is their normal adjustment, it is of advantage 85 to provide a means to lock said sections in such relation and as herein disclosed one of the cuffs or sleeves 4 has pivotally engaged therewith a latch 7 which is engaged with an outstanding headed member 8 carried by 90 the second cuff or sleeve 4 whereby the sections 1 and 2 are effectively locked and held in their extended relation.

When it is desired to shorten the pole as in a restricted passageway, it is only necessary to disengage the latch 7 from the member 8 to permit the sections 1 and 2 to be moved inwardly one relative to the other.

This adjustment of the pole is of particular advantage in connection with a mine locomotive as it permits the pole to be turned without knocking down slate or the like which would otherwise be liable to fall upon the operator as now occurs with frequency, resulting in injury and oftentimes death. 100

From the foregoing description it is thought to be obvious that a trolley pole constructed in accordance with my invention is particularly well adapted for use by reason of the convenience and facility with 110

which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A trolley pole comprising two sections having adjacent end portions in overlapping relation, the inner end of each section being provided with a sleeve through which the inner end portion of the second section is slidably projected, and co-acting means car-

ried by said sleeves for locking the sections against relative movement.

2. A trolley pole comprising two sections having their inner end portions in overlying relation, a cuff carried by the inner end portion of each of the sections through which the inner end portion of the second section is slidably disposed, the cuffs of the sections contacting to limit the outward relative movement of the sections, each of said sections having extending therefrom an elongated member provided with an outstanding lug to limit the relative inward movement of the sections.

In testimony whereof I hereunto affix my signature.

JOHN A. SANNER.
